Attorney

UNITED STATES PATENT OFFICE.

JAMES HARLAN MILLS, OF GALLIPOLIS, OHIO.

INNER-TUBE RECEPTACLE.

1,383,962.

Specification of Letters Patent. Patented July 5, 1921.

Application filed June 28, 1920. Serial No. 392,251.

To all whom it may concern:

Be it known that I, JAMES HARLAN MILLS, a citizen of the United States, residing at Gallipolis, in the county of Gallia and State 5 of Ohio, have invented certain new and useful Improvements in Inner-Tube Receptacles, of which the following is a specification.

This invention relates to containers or receptacles, more particularly to receptacles for the extra or surplus inner tubes of pneumatic tires usually carried with motor driven vehicles upon which pneumatic tires are employed, and has for one of its objects 10 to provide a simply-constructed device in which two or more of the tubes having the air valves attached, may be disposed and protected from injury or from contact one with the other, and from which any tube 15 may be removed without disturbing the others.

With these and other objects in view, the invention consists in certain novel features of construction as hereinafter shown and 20 described and then specifically pointed out in the claim, and in the drawings illustrative of the preferred embodiment of the invention.

Figure 1 is a perspective view of the improved container in open position and without its supply of inner tubes.

Fig. 2 is a plan view with the cover raised as in Fig. 1, with a pair of inner tubes arranged therein.

The inner or inflatable tubes of pneumatic tires are of rather fragile material, easily punctured or otherwise impaired if roughly used, and generally one or more extra tubes are carried with each motor driven 35 vehicle, and to safely carry these surplus tubes and to retain them in an easily accessible position is the principal object of the present invention.

The improved device includes a casing or 40 body 10 preferably oblong and having a cover 11 hingedly united thereto at 12.

The casing and its cover may be of any suitable material, but will generally be of sheet metal and provided with a suitable 45 fastening or locking means represented conventionally at 13. The body portion is pro-

vided preferably with a stop bead 14 against which the edge of the closure or cover bears when closed.

Disposed within the casing 10 is a U-shaped partition including a closed end portion 15 and side members 16, the ends of the latter being attached at 17 to one wall of the receptacle. By this means a U-shaped pocket is produced in which three walls of 60 the casing and the three parts of the partition form the walls of the pocket.

Within the above mentioned U-shaped partition is another and smaller U-shaped partition including a closed end portion 18 65 and spaced side portion 19, the ends of the sides being attached at 20 to the closed end portion 15 of the outer partition. For the purpose of this description the partition formed of the members 15 and 16 will be 70 referred to as the outer partition, and the partition formed of the members 18 and 19 as the inner partition.

The space between the partitions forms another U-shaped pocket as illustrated more 75 clearly in Fig. 1.

Formed in the end member 15 of the outer partition is a recess or opening 21, and formed in the end member 18 of the inner partition is a like recess or opening 22.

The U-shaped pockets produced by the partitions are designed to receive the inner tubes represented at 23, when deflated and folded as shown in Fig. 2, and the openings 21 and 22 receive the air valve tubes 24, and 85 thus safely hold the tubes and prevent injury thereto during transportation.

The space within the inner partition not occupied by the valve tubes 24 may be utilized to hold various small tools or accessories, and additional partitions may be inserted, as indicated by dotted lines in Fig. 2, if required, to protect the valve tubes from contact with such articles.

The preferred embodiment of the invention is disclosed in the drawings and set forth in the specification, but it will be understood that any modifications within the scope of the claims may be made in the construction without departing from the principle of the invention or sacrificing any of its advantages.

What I claim is:

A container having an outer U-shaped partition therein united at the ends of its side members to one wall of the container, 5 and an inner and smaller U-shaped partition within the outer U-shaped partition with the ends of its side members united to

the closed end of the outer partition, whereby interengaging U-shaped spaces are provided within the walls of the container. 10

In testimony whereof I affix my signature hereto.

JAMES HARLAN MILLS.
